UNITED STATES PATENT OFFICE.

ERICH H. LICHTENBERG, OF MILWAUKEE, WISCONSIN, ASSIGNEE TO KOEHRING MACHINE COMPANY, OF MILWAUKEE, WISCONSIN.

CONCRETE-MIXER-LOADING BUCKET.

1,223,185.

Specification of Letters Patent. Patented Apr. 17, 1917.

Application filed September 8, 1913. Serial No. 788,741.

To all whom it may concern:

Be it known that I, ERICH H. LICHTENBERG, a citizen of the United States, residing at Milwaukee, in the county of Milwaukee and State of Wisconsin, have invented certain new and useful Improvements in Concrete-Mixer-Loading Buckets, of which the following is a specification.

The present invention appertains to the art of concrete mixing machines and comprises essentially certain novel means for facilitating the charging of the mixing drum of mixers of the above class with the materials which are to be mixed thereby.

While the invention is particularly designed and preferably operated conjointly with a mixing machine, it will be understood that the improvements hereinafter set forth are susceptible of employment for general purposes in charging or loading a receptacle or the like.

In the practical embodiment of the invention, it is contemplated to utilize a charging bucket made in two sections, one of which, the delivery section, is suitably pivoted to a supporting frame, and the other of which, a receiving section, is pivotally connected with the delivery section for movement relative thereto and for movement therewith.

Included in the invention are special hoisting means controlling the raising and lowering movement of the charging bucket, peculiar means for mounting the bucket upon its support, and a bumper for relieving the shock incidental to the dropping of the bucket to the position in which it is to receive a load of materials for subsequent discharge thereby.

In the accompanying drawings, Figure 1 is a side elevation showing a charging bucket and coöperating supporting and operating instrumentalities constructed in accordance with the essential features of the invention; and

Fig. 2 is a front elevation of the bucket and certain parts of the hoisting mechanism, the frame and truck upon which the bucket is mounted being omitted.

In the drawings, A designates a truck of any suitable construction and preferably one such as ordinarily carries the mixing drum B and associated driving mechanism of a conventional type of concrete mixer. The frame-work C in which the drum B is mounted extends upwardly from said drum

a suitable distance and supports thereon a winding shaft 1 with which certain cables constituting the operating means for the charging bucket of the invention, are connected in a manner hereinafter more fully described. Near the lower portion of said framework C are supplied offstanding brackets 2 carrying a pivot 3 forming the axis upon which the bucket D is mounted for bodily movement.

The bucket D comprises an upper delivery section D' and the lower receiving section D'', both of said sections tapering upwardly toward the receiving opening of the mixing drum B as shown most clearly on reference to Fig. 2. The delivery section D' of the bucket has an arm or casting 4 suitably attached to its upper end and connected to the brackets 2 by the pivot 3 aforesaid. The lower receiving section D'' of the bucket is of angular shape as seen in Fig. 1 and is hinged at a point intermediate its inner end as shown at 5 to the lower end of the delivery section D'. Having in view, therefore, the relative arrangement of the sections of the bucket it will be apparent that the inner end of the section D'' upon upward movement of said section is adapted to move relative to the section D' extending partially into the latter, so as to insure the proper passage of the contents of the first-mentioned section into the delivery section D' in the loading or charging operation. Secured to the opposite sides of the lower section D'' of the bucket are the hoisting cables 6 which pass upwardly over the sheaves 7 mounted on the pivoted arms 9 carried by the uppermost portion of the delivery section D'. The trunnions 8 form the axes of arms 9 which are connected therewith between their ends and carry the sheaves 7 and 10 at the opposite ends, said sheaves 10 engaging the cables 6 on the sides of the latter opposite those at which the sheaves 7 are located. In other words, each cable 6 passes between an adjacent pair of the sheaves 7 and 10 and the sheaves 10 are movable bodily with the arms 9, independently of their rotation on said arms owing to the fact that when the bucket is raised into its dotted line position shown at x in Fig. 1, the points of connection of the cables 6 with the bucket are considerably elevated above the drums 11 on the winding shaft 1, about which drums the cables 6 are adapted

to wind. The hoisting of the bucket D is accomplished by operation of the winding shaft 1 which in addition to carrying the drums 11 has also fixed thereon a main drum

5 12. A driving cable 13 is connected with the drum 12 and passes therefrom to any suitable controlling and coöperating mechanism, the latter not being described, because immaterial in so far as the present invention is concerned, since any operating mechanism

10 may be employed for actuating the shaft 1.

Having in view the foregoing, it will be understood that with parts arranged in the full line position shown in Fig. 1, after a

15 load of materials has been dumped upon the bucket section D'' the cable 13 or equivalent means will be operated to raise the bucket.

Upon initial movement of the cable 13 the cables 6 are wound around the drums 11 and the bucket section D'' is raised by pivotal movement at the hinged points 5 until the inner end of said section practically abuts with the bottom of the section D' and until abutments 14 in the form

20 of angle plates 15 on the sides of the section D'' abut with the lower end of said section D'. Preferably the lower end of said section D' is provided at opposite sides with the angle plates 15 to engage the abutments

25 or plates 14 just mentioned. The bucket section D'' moves independently of the section D' until said section D'' reaches the dotted line position designated y in Fig. 1 where-

30 upon the further movement of the cables 6 causes the two bucket sections to move upward to their discharging position by simultaneous movement. In dumping it is evident that the contents of the bucket section D'' pass therefrom through the delivery section D' into the mixing drum.

On reversing operation of the movement of the cable 13 to lower the bucket, the two sections move together until the upper section D' rests upon the adjacent end of the truck A and thereafter the section D'' moves

45 on downwardly to its full line position in Fig. 1. To retard the final movement of the sections D'' and D' a bumper 16 is interposed between the adjacent end of the

50 truck A and the inner and outer ends respectively of said bucket sections, said bumper comprising a curved spring of suitable strength with which the inner end of the section D'' is adapted to abut as it drops to its extreme lower position, the spring simultaneously engaging the section D'.

When the bucket of the machine is not being used the bucket section D'' will be raised to the dotted line position y in Fig. 1 and bolts designated 17 and illustrated in dotted lines in Fig. 1 will be passed through the abutment 14 and the plate 15 thereby rigidly connecting the members D' and D'' together, the latter elevated from the ground and the

65 bucket practically inoperative temporarily.

Owing to the peculiar manner in which the sheaves 7 and 10 coöperate with the cables 6 it will be seen that a much lower and compact supporting framework C may be employed, than would otherwise be required with as large a bucket as is used.

The form of the bumper spring 16 is such that it is compressed by the section D'' as the latter drops and the free end of the spring is forced upward to engage the section D' as it reaches the truck.

Having thus described the invention, what I claim as new is:

1. In charging mechanism for concrete mixers, the combination of a support, a bucket comprising a delivery section pivoted at one end to said support, a receiving section pivoted to the other end of the delivery section, an operating cable for raising the bucket connected with the receiving section, sheaves on the delivery section over which said cable passes, and means intermediate said sections whereby initial movement of said cable causes movement of the receiving section independently of the delivery section and subsequent movement of the cable moves the two sections simultaneously to a dumping position.

2. In charging mechanism for mixers, the combination of a bucket including inner and outer bucket sections normally inclining downward to receive a charge of material, a support, a pivotal connection between the support and the inner section, a pivotal connection between the sections, and means to raise the outer section initially to cause the same to coact with the inner section whereby to lift the sections simultaneously to an inclination opposite the normal one, for discharging the bucket.

3. In charging mechanism for concrete mixers, the combination of a support, a bucket comprising a delivery section pivotally connected at one end with said support, a receiving section of angular form pivotally connected at a point intermediate its inner end with the other end of the delivery section, cable means connected with the receiving section of the bucket, and an abutment carried by said receiving section to engage the delivery section whereby to cause simultaneous movement of the two sections at a predetermined point in the movement of the receiving section.

4. In charging mechanism for concrete mixers, the combination of a support, a bucket comprising a delivery section pivotally connected at one end with said support, a receiving section of angular form pivotally connected at a point intermediate its inner end with the other end of the delivery section, cable means connected with the receiving section of the bucket, and an abutment carried by the inner end portion of the receiving section and adapted to engage the

outer adjacent end of the delivery section at a predetermined point in the movement of the receiving section.

5. In charging mechanism for concrete mixers, the combination of a support, a bucket comprising a delivery section pivotally connected at one end with said support, a receiving section of angular form pivotally connected at a point intermediate its 10 inner end with the other end of the delivery section, cable means connected with the receiving section of the bucket, an abutment carried by the inner end portion of the receiving section and adapted to engage the 15 outer adjacent end of the delivery section at a predetermined point in the movement of the receiving section, sheaves on the delivery section over which said cable means passes, arms pivoted to the delivery section, and 20 sheaves carried by said arms and also engaging said cable means from the side opposite that at which the first mentioned sheaves are arranged.

6. In charging mechanism for concrete mixers, the combination of a support, a bucket comprising a delivery section pivotally connected at one end with said support, a receiving section of angular form pivotally connected at a point intermediate its 25 inner end with the other end of the delivery section, cable means connected with the receiving section of the bucket, an abutment carried by the inner end portion of the receiving section and adapted to engage the 30 outer adjacent end of the delivery section at a predetermined point in the movement of the receiving section, sheaves on the delivery section over which said cable means passes, arms pivoted to the delivery section, sheaves 35 carried by said arms and also engaging said cable means from the side opposite that at which the first mentioned sheaves are arranged, a winding shaft, and drums on said shaft over which the cable means passes and 40 located in a plane below that in which the last-mentioned sheaves are adapted to move on raising of the bucket to dumping position.

7. In combination, a supporting framework, a loading bucket mounted thereon, and movable into a dumping position in which it projects above the said framework, winding mechanism on the framework, cables connected with said winding mechanism and with the bucket, spaced sheaves on the bucket between which each cable operates, and pivoted arms directly supporting the said sheaves and shiftable according to the movement of the bucket.

8. In combination, a support and framework thereof, a bucket comprising an inner section pivoted to said framework, and an outer section, means connected with the outer section to raise and lower the same, the inner section being adapted to be lowered to 60 abut with the support and to be held in a predetermined position thereby, and a movable connection between the outer section and the inner section whereby the outer section is adapted to move after the inner section comes to rest on the support.

9. In charging mechanism for concrete mixers, the combination of a support and a framework thereon, charging bucket mechanism including an upper section pivotally mounted upon said framework and movable into a downwardly inclined position resting upon said support, a lower receiving section pivoted to the outer portion of said upper section and having an abutment flange cooperative with the adjacent end portion of the upper section, and means for raising said bucket mechanism including a cable connected with the receiving section to elevate the same and cause operative abutment of the flange of said receiving section with the said upper section whereby said sections are adapted to move together a portion of the discharging movement of the receiving section.

In testimony whereof I affix my signature in presence of two witnesses.
